UNITED STATES PATENT OFFICE.

JOSEPH E. JAROS, OF CHICAGO, ILLINOIS.

HYPODERMIC SYRINGE.

Application filed February 27, 1925. Serial No. 11,908.

My invention pertains to a hypodermic syringe, and one which is especially suitable for use by dentists. The main object of this invention is to provide a durable, simple and efficient construction of this kind; and another object is to provide a syringe in which the needle is fixed or integral with the end of the barrel, preferably by fusing the glass of the barrel end around a needle consisting 10 of material having a high point of fusion.

Other objects will appear hereinafter.

The invention consists in the combinations and arrangements of parts hereinafter described and claimed.

15 The invention will be best understood by reference to the accompanying drawings forming a part of this specification, and in which,

Fig. 1 is a longitudinal section of the 20 syringe barrel with cap means and a compound cork mounted thereon to close the barrel, as when filled;

Fig. 2 is a horizontal sectional view taken on line 2-2 of Fig. 1;

25 Fig. 3 is an elevation of the complete syringe, ready for use, and partly shown in section;

Fig. 4 is a longitudinal section of the barrel, closed simply by means of an inner cork;

30 Fig. 5 is a longitudinal section of a slightly modified form of cap means and plunger; and

Fig. 6 is an elevational view of the modified form of syringe.

35 The form of invention illustrated in Figs. 1, 2 and 3 comprises a glass barrel or tubular member 10 having a rim 11 at its upper open end 12 and having a solid integral portion 13 at the lower end with a hollow needle

40 14 fixedly mounted therein, and preferably by fusing the glass of the solid portion 13 around said needle, so that the channel 15 in the needle extends from the chamber 16 in the barrel and beyond the exterior of the

45 portion 13. The needle 14 is made from material having a high point of fusion, and preferably of iridio-platinum.

Closure means is provided for the upper 50 end of the barrel, and this means preferably includes cap means and a compound cork mounted therein. The cap means preferably comprises a cap 17 mounted over the tube, and a sleeve 18 mounted around the tube and having finger lugs 19 extending therefrom.

55 The upper end 20 of the sleeve is threaded to engage in the lower threaded portion of

cap 17, and bears under rim 11 of the barrel. The compound cork includes a sleeve 21 which is mounted in the cap and is seated beneath the top of the cap and upon the 60 rim 11 of the barrel, thus forming cushioning means between the cap and barrel, and this cork further includes a core 22 within sleeve 21, which core is of an exact size to move into and fit closely in the barrel 10. 65

Plunger means is provided and comprises a stem 23 engageable through an opening 24 in the top of cap 17, and a nut 25 removably mounted on its inner end to prevent accidental withdrawal of the plunger from 70 said cap during operation. This plunger has a head or hand piece 26 on its upper end and curved lugs 27 and 28 thereon as shown. This plunger is adapted to move the core 22 of the cork into the chamber 16 within 75 barrel 10, as indicated in Fig. 3 of the drawings, to force the solution through the channel 15 in needle 14, as is well understood.

Figs. 4, 5 and 6 illustrate a slightly modified form of closure means, however, the 80 glass barrel 10 is identical with that in the preceding form and is provided with the rim 11 at the upper end, and the closed integral portion 13 at the lower end in which the hollow needle 14 is fixedly mounted, as 85 indicated in Fig. 4, but in this form the inner core 22 of the cork is used alone to form the sealing means or closure means for the barrel, for shipping the solution in said barrel and for retaining the same. In this 90 form, however, the cap 17' is slightly modified and is preferably provided with a shoulder portion 17'' which directly engages or rests upon the glass rim 11', as shown in Fig. 6, thus doing away with the use of the 95 sleeve portion of the cork, shown in the preceding form. A sleeve 18' with finger lugs 19' is also provided and has its upper portion 20' threaded for engagement with the threads in cap 17', said portion 20' engaging beneath rim 11', and being preferably identical in all respects with the sleeve means shown in the preceding form. The plunger 23' with its removal nut 25' and head or hand engaged portion 26' is also the same as 100 105 in the preceding form.

The form shown in Figs. 4, 5 and 6 is more economical than the preceding form, since the barrel 10 with the cork portion 22 alone need be transmitted in refilling the 110 barrel and in delivering it to the dentist or user; whereas in the form shown in Figs.

1, 2 and 3 it has been customary to transmit the cap 17 and sleeve 18 along with the cork 21, 22, mounted upon the barrel, as shown in Fig. 1, when the barrel is being 5 transmitted for refilling and when it is delivered filled to the dentist or user; whereas the sleeve 21 of the cork acts as a cushioning means between the cap 17 and rim 11, while in the form shown in Fig. 6 the cap 10 bears directly on the rim 11'.

While I have illustrated and described the preferred form of construction for carrying my invention into effect, this is capable of variation and modification without departing 15 from the spirit of the invention. I, therefore, do not wish to be limited to the precise details of construction set forth, but desire to avail myself of such variations and modifications as come within the scope of 20 the appended claims.

Having described my invention, what I claim as new and desire to secure by Letters Patent is:

1. A syringe comprising a barrel with cap 25 means mounted thereon, and a compound cork including a sleeve mounted in said cap means to engage the end of said barrel and a core in the sleeve movable into the barrel.

2. A syringe comprising a barrel, cap 30 means with a plunger mounted on said barrel, and a cork including a sleeve seated between said cap means and the end of said barrel and a core in said sleeve movable by said plunger into said barrel.

3. A syringe comprising a barrel with an 35 upper rim, a cap mounted on said rim, a sleeve mounted beneath said rim and removably fastened to said cap to hold it on the barrel, and a cork mounted in said cap and including a sleeve portion seated against 40 said rim and a core portion movable into said barrel.

4. A syringe comprising a barrel with a rim, a cap mounted over said rim, a sleeve mounted on said barrel beneath said rim and removably fastened to said cap to hold it on the barrel, a cork including a central core 45 and a sleeve portion around the same which is seated in said cap against said rim, and a plunger mounted in said cap to move therein and force said core into said barrel.

5. A syringe comprising a glass barrel with an integral upper rim and a solid integral lower end, a hollow needle fixed in said end by fusing the glass thereof around said needle, a sleeve with finger engaging means mounted on said barrel to engage said rim, a cap mounted over said rim and threaded to said sleeve, a cork with a core and a sleeve thereon which is seated in said cap and 50 against said rim, and a plunger mounted to move in said cap and having means to prevent withdrawal therefrom for moving said core into said barrel.

In testimony whereof I have signed my 55 name to this specification.

JOSEPH E. JAROS.
